UNITED STATES PATENT OFFICE.

JOHN H. V. FINNEY AND SAMUEL A. WALKER, OF BOULDER, COLORADO.

CARBURETER ATTACHMENT.

1,262,317.

Specification of Letters Patent.

Patented Apr. 9, 1918.

Application filed November 12, 1917. Serial No. 201,555.

To all whom it may concern:

Be it known that we, JOHN H. V. FINNEY and SAMUEL A. WALKER, citizens of the United States, residing at Boulder, in the 5 county of Boulder and State of Colorado, have invented certain new and useful Improvements in Carbureter Attachments, of which the following is a specification, reference being had to the accompanying drawings.

This invention relates to certain improvements in carbureter attachments, and it is an object of the invention to provide a device of this general character adapted to be 10 inserted between the carbureter and the intake and which is provided with novel and improved means whereby heavy particles of fuel which may be drawn from the carbureter are effectively broken up or comminuted and thereby improving the mixture, saving fuel and resulting in the engine running smooth and starting easy.

The invention consists in the details of construction and in the combination and arrangement of the several parts of our improved carbureter attachment wherein certain important advantages are attained and the device rendered simpler, less expensive and otherwise more convenient and advantageous for use, as will be hereinafter more fully set forth.

The novel features of our invention will hereinafter be definitely claimed.

In order that our invention may be the 25 better understood we will now proceed to describe the same with reference to the accompanying drawings wherein:

Figure 1 is a sectional view taken through an attachment constructed in accordance 30 with our invention, the co-acting parts of the intake and carbureter being shown in fragment;

Fig. 2 is a sectional view taken substantially on the line 2—2 of Fig. 1; and

Fig. 3 is a transverse sectional view taken 45 through one of the parts or sections of the casing as herein employed.

As disclosed in the accompanying drawings our improved attachment consists of 50 a casing comprising two sections or members M of duplicate construction. Each of the members M comprises a plate 1 having produced at its axial center an opening 2 adapted to register with either the intake I 55 or outlet of the carbureter C. The marginal portion of the plate 1 is defined by a lat-

erally directed flange 3 and when in assembled relation the free marginal portions of the flanges 3 of the members 1 are adapted to contact whereby an inclosed casing or housing is afforded. The inner faces of each of the flanges 3 have its marginal portion defined by an annular recess 4 in which is adapted to seat a marginal portion of an annular member 5. The member 5 is preferably formed of copper so that when the members M are in assembled relation the joint at the contacting edges of the flanges 3 will be sealed. Each of the sections or members M is provided with a diametrically opposed ear 6 provided with the slots 7 through which are adapted to be directed the clamping bolts 8 which also co-act in a conventional manner with the flanges 9 arranged at the adjacent ends of the intake 10 I and the outlet of the carbureter C. Each of the flanges 3 adjacent its inner end is provided with an annular shoulder 10 upon which is adapted to contact the marginal portion of a disk 11. In practice we 15 find it of advantage to employ six disks 11 in superimposed relation although we do not wish to be understood as limiting ourselves to this exact number. Each of the disks 11 is provided with the perforations 11 or restricted openings 12 and as illustrated in Fig. 1 it is to be noted that when in assembled relation the openings 12 of the disks 11 are so arranged that the openings 12 in one disk will be exposed to a solid 20 portion of the disk or disks immediately adjacent thereto so that the mixture will pass through our improved attachment in a staggered path of travel so that breaking up or comminuting of any heavy particles of fuel 25 in the mixture is assured.

We also find it of advantage to interpose between the marginal portions of adjacent disks 11, when in assembled relation, the expandable washers 14 preferably formed 30 of wire and suitably crimped. By this arrangement it will be perceived that the washers 14 will permit the disks 11 to be sufficiently compacted to properly fit within the assembled sections or members M, at 35 the same time maintaining said disks 11 in separated relation.

The flange 3 of each of the sections or members M is provided with a transversely disposed and inwardly directed rib or key 14 40 15 which is adapted to be seated within a notch 16 produced in the periphery of each

of the disks 11 and thereby holding said disk against rotation. As herein embodied each of the disks 11 is provided with two diametrically opposed notches 16 so that in assembling the device adjacent disks 11 may be reversed one relative to the other so that the openings 12 in one disk will be in staggered relation relative to the openings in the second disk as has hereinbefore been referred to.

From the foregoing description, it is thought to be obvious that a carburetor attachment constructed in accordance with our invention is particularly well adapted for use by reason of the convenience and facility with which it may be assembled and operated and it will also be obvious that our invention is susceptible of some change and modification without materially departing from the principles and spirit thereof and for this reason we do not wish to be understood as limiting ourselves to the precise arrangement and formation of the several parts herein shown in carrying out our invention in practice except as hereininafter claimed.

We claim:

1. A device of the character described comprising a casing, opposed walls of said casing being provided with openings, per-

forate disks arranged within the casing in superimposed relation, crimped washers interposed between the marginal portions of the disks for maintaining the same in spaced relation, and means for holding said disks against rotation independently of the casing.

2. A device of the character described comprising a casing, opposed end walls of said casing being provided with openings, an inwardly directed rib extending longitudinally of the side wall of the casing, separable perforate disks arranged within the casing in superimposed relation, the marginal portions of said disks being provided with notches to receive the key of the casing whereby said disks are held against rotation independently of the casing, and means separable from the disks and the casing and interposed between the marginal portions of the disks for maintaining said disks in separated relation.

In testimony whereof we hereunto affix our signatures in the presence of two witnesses.

JOHN H. V. FINNEY.
SAMUEL A. WALKER.
